FOREIGN PATENT DOCUMENTS

EM 004810000-0001 * 3/2018

Primary Examiner — Paula Allen Greene

(57) **CLAIM**

The ornamental design for a speaker decoration net, as shown and described.

DESCRIPTION

FIG. 1 is a front elevational view of a speaker decoration net showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front perspective view thereof;

FIG. 8 is another front perspective view thereof;

FIG. 9 is a rear perspective view thereof; and,

FIG. 10 is another rear perspective view thereof.
